UNITED STATES PATENT OFFICE

2,109,018

FACIAL MASK

William Grant Thurber, Santa Monica, Calif.

Application June 11, 1935, Serial No. 26,058

2 Claims. (Cl. 128—164)

This invention relates to apparatus and means for treatment of disorders in the head, facial conditions and the like.

An object of this invention is to provide a means in the form of a mask which may be conveniently applied to the face and head of an individual and which includes means whereby the entire device may be heated so as to place the portions of the head covered by the mask under a predetermined temperature for treatment of the skin or infected portions of the head.

Another object of this invention is to provide a device of this character which is so constructed that it may be applied to the head of an individual in either an upright or reclining position and which also includes means whereby medicated vapors may be inhaled by the wearer of the device during the time that the mask is applied to the head.

A further object of this invention is to provide a device of this kind which, when in applied position, and used as an inhaler will permit the inhalation of medicated vapors and the exhalation to the atmosphere of the air so that the impure air exhaled by the lungs will not contaminate the medicated vapors inhaled through the device.

A still further object of this invention is to provide a device of this character which may be used in beauty treatments or the like, that is for treatment of the skin and which is so constructed that substantially the entire face may be covered up without impairing the breathing of the wearer.

Still another object of this invention is to provide in a device of this kind, means whereby the wearer may inhale medicated vapors in either one or both of the nostrils.

A further object of this invention is to provide a device of this character which is so constructed that the heat applied to the device will volatilize a medicated compound so that heated vapors of a medicated composition will be drawn into one or the other or both of the nostrils for treatment of the respiratory tract.

The above and various other objects and advantages of this invention will in part be described in, and in part be understood from the following detail description of the present preferred embodiment, the same being illustrated in the accompanying drawing wherein:

Figure 1 is a longitudinal section partly broken away of a device constructed according to an embodiment of this invention.

Figure 2 is a rear elevation of the air controlling means.

Figure 3 is a section taken on the line 3—3 of Figure 2.

Figure 4 is a section taken on the line 4—4 of Figure 3.

Figure 5 is a section taken on the line 5—5 of Figure 3.

Referring to the drawing wherein like numerals of reference designate corresponding parts throughout the several views, the numeral 10 designates generally a mask which is adapted to substantially cover the entire face and, if desired, may be of a size to cover a considerable portion, if not all of the head of the wearer. This mask 10 may be either of a flexible or a relatively rigid construction and is provided with a plurality of resistance wires 11 which are embedded in the mask body 10 and adapted to be connected to a suitable source of electric current 10 supply for the purpose of electrically heating the structure of the mask.

This mask 10 has a nasal chamber 13, provided with an opening 12, and in this opening 12 a shutter structure, generally designated as 14, is positioned. This shutter structure comprises a frame 15 provided with guides 16 in which a pair of shutters or valve members 17 are slidably mounted. These valve members 17 have pivotal connection, as at 18, with the guides 16 and preferably the shutters 17 are adapted to be disposed in one of two positions.

In one or the outermost or lower position, the shutters are adapted to rock in a movement toward or away from the nasal chamber 13, and in any position except the innermost position, the shutters 17 are locked against rocking movement by means of locking members 19 provided in the guides 16, adjacent the outer portion thereof. When the shutters 17 are in their outermost position, the wearer of the device may freely inhale or exhale through the mask.

When the shutters 17 are in their outermost or lower position, the person may only exhale through the frame 14 and inhalation is had through an intake pipe 20 which opens into the nasal chamber 13 and extends along the lower portion of the mask 10. The lower or outer end of the inhaling pipe or pipes 20 has a flexible tube 21 connected thereto and this flexible intake pipe 21 is connected to an outlet pipe 22 carried by a vaporizing member 23. The vaporizing member 23 comprises a container or receptacle 24 adapted to receive a volatile fluid and an air inlet pipe 25 is carried by the receptacle 20 and 50 55

opens into the atmosphere so that air may be freely drawn through the pipes 20 and 21 with the air passing through the volatile fluid carried by the receptacle 24. The mask 10 has a pair of spaced apart ears or lugs 26 provided with openings in which pins 27 carried by the receptacle 24 are adapted to engage. As the incoming air containing the medicated vapor passes through the pipe 20, this incoming vapor or medicated air is heated by the mask so that the air inhaled in the nasal chamber will be of a predetermined temperature in addition to being vaporized from the receptacle 24.

Free inhalation and exhalation may be had through the frame 15 from one or both sides of the nostril by moving one or both of the shutters 17 upwardly. The shutters 17 will be held in their uppermost or inoperative position by the frictional engagement of the guides 16 with the

20 trunnions 18.

Preferably, the shutter frame is disposed at an angle relative to the vertical when the person is in a reclining position so that the shutters or valve members 17 will gravitatively swing to a closed position. The frame 15 has cushioning members 28 against which the shutters 18 engage when in closed position so that there will not be any noise in the closing of the shutters during the inhaling operation.

30 Where the device hereinbefore described is used in an upright position by the wearer, springs or like means may be provided to normally swing the shutters or valve members 17 to a closed position.

35 In the use of this device, the body 10 may be applied to and secured to the head of the wearer, preferably about the face, and partially about the side of the head and face with the resistance means 11 connected to a suitable source of electric current supply. Where the device is merely used for facial treatments or the like, the shutters 17 may be moved to their outermost position where they are locked against swinging movement and in which position the nasal chamber 45 13 is open to the atmosphere. The wearer of the device may then freely inhale and exhale through the frame 15 and the opening 12 in the frame.

In the event, however, that it is desired to use this device for treatment of the respiratory tract, either one or both of the shutters or valves 50 17 may be moved to their innermost position in which position these shutters or valves 17 will gravitatively swing to closed position but will be moved to open position by exhaling into the nasal chamber 13. The receptacle 24 may be attached to the lugs 26 and the pipes 20 connected to the pipes 22 by means of flexible pipe connections 21. In this manner, the person wearing the device will inhale medicated vapors 55 by reason of the fact that substantially all air drawn into the nasal chamber must first pass through the receptacle 24 and by reason of the

fact that this receptacle is partly heated in order to vaporize the volatile liquid disposed therein. It will be apparent from the foregoing that an exceedingly simple device has been constructed for use in treatment of head disorders 5 or disorders of the respiratory tract, in addition to treatment of the exterior surface of certain portions of the head, particularly the face.

Where this device is applied to the face of a patient, a sanitary protector in the form of a 10 relatively flexible parchment sheet is first placed upon the face of the patient in order that the medicated vapors will not contact directly with the face of the patient. It will also be understood that the parchment protector may be 15 omitted and an absorbent and medicated pack used in place thereof so that the heat from the mask will draw out the medicinal compound of the pack or treatment of the skin.

The shutters 17 may be locked in their innermost position, as shown in Figure 2, by means of locking members 16a.

I claim:—

1. An inhaling means comprising a member 25 adapted to engage over the face of an individual and provided with a nasal chamber, a frame carried by said chamber, said frame including a plate, pairs of guide members secured to said plate and extending below one edge thereof, that portion of the guide members below said plate 30 defining a pair of openings providing communication between said chamber and the atmosphere, a pair of flap valves disposed one between each pair of guide members, trunnions carried by said valves and engaging said guide members 35 to slidably and swingably support said valves within said frame, said plate holding said valves against swinging movement when said valves are raised within said guide members to an inoperative position behind said plate, into said chamber and means for discharging a vapor.

2. An inhaling means comprising a member 40 adapted to engage over the face of an individual and provided with a nasal chamber, a frame carried by said chamber, said frame including a 45 plate, pairs of guide members secured to said plate and extending below one edge thereof, that portion of the guide members below said plate defining a pair of openings providing communication between said chamber and the atmosphere, 50 a pair of flap valves disposed one between each pair of guide members, trunnions carried by said valves and engaging said guide members to slidably and swingably support said valves within said frame, said plate holding said valves against 55 swinging movement when said valves are raised within said guide members to an inoperative position behind said plate, and means carried by said frame for locking a selected valve against swinging movement when disposed in operative 60 position.

WILLIAM GRANT THURBER.
